APPARATUS FOR COATING METAL STRIP
OR WIRE

Ernest B. Plott and John S. Stanier, Youngstown, Ohio, assignors to The Youngstown Sheet & Tube Company, Youngstown, Ohio, a corporation of Ohio

Application October 31, 1940, Serial No. 363,650

1 Claim. (Cl. 91—12.5)

This invention relates to the coating of metal in the form of strip or wire. It will be described herein as applied specifically to the application of a protective coating such as zinc to ferrous strip although the principles of the invention may be applied as well to the coating of other materials such as wire.

In the coating of sheet metal or wire as heretofore carried out, the base metal has been pickled in an acid solution prior to passing through a bath of molten zinc. The pickling operation is quite costly because of the expense of providing and maintaining the necessary equipment. In addition, it requires a considerable amount of time, and working conditions in the vicinity of the pickling equipment are quite severe unless expensive precautions are taken.

We have invented a novel apparatus for coating sheet metal and particularly ferrous strip or wire, whereby the aforementioned objections are overcome. In a preferred embodiment and practice of the invention, we provide means for mechanically descaling the strip progressively prior to the actual coating. We then pass the strip progressively through a coating bath and suspend it on emerging therefrom, free from contact with any support for a period sufficient to cause solidification of the coating. The strip is then sheared into lengths or coiled.

The accompanying drawings illustrate diagrammatically the embodiment and practice outlined above and a modification thereof. In the drawings,

Fig. 1 is a central, longitudinal, sectional view through several pieces of apparatus which operate successively on the strip; and

Figs. 2 and 3 together constitute a similar view of a modification.

Referring now in detail to the drawings, the apparatus of our invention includes an uncoiler indicated diagrammatically by coil-supporting rolls 18 adapted to hold a coil of strip 14 while being unwound and processed in single thickness, the portion of the coil passing through the processing apparatus being designated S.

Adjacent the uncoiler is a device 12 for joining successive coils end to end. This device may be a butt-welder or a stitcher, both of which are well known and require no detailed description. The device 12 preferably includes a guide roll 13 and driven pinch rolls 14 on opposite sides thereof together with strip-engaging parts 15 which may be electrodes if the device is a welder, or dies if the device is a stitcher.

Spaced from the strip-joining device 12 is a

descaling apparatus 16. This apparatus includes a guide roll 17, driven entering and exit pinch rolls 18 and 19, bending rolls 20 and 21, and abrasion devices 22, preferably rotary wire brushes. The descaling apparatus is enclosed in a housing 16a. As shown in the drawings, the strip is pulled from the coil 11 by the pinch rolls 14 and is fed through the descaling apparatus 16. After passing over the guide roll 17 and through the pinch rolls 18 thereof, it is bent in opposite directions around the bending rolls 20 and 21 prior to passing through the pinch rolls 19 and out of the descaling apparatus. The pinch rolls 18 and 19 maintain the strip taut and thereby insure that it is sharply bent progressively in opposite directions, beyond the elastic limit.

The bending of the strip around the rolls 20 and 21 causes the layers of scale adhering to the surfaces thereof to be fragmented and at least partly detached. The bending also loosens the bond between the scale and the base metal to an extent that any fragmented particles not immediately detached may readily be removed by abrasion. This is effected by the rotary wire brushes, which engage opposite surfaces of the strip at points where they are convexly bent. After the strip has passed through the apparatus 16, it is entirely scale-free and ready for coating.

The coating apparatus 23 is located closely adjacent the descaling apparatus 16 and preferably comprises a pot 24 or other suitable container for a bath of coating material such as molten zinc, the surface of which is indicated at 25. Entry rolls 26, bottom rolls 27 and exit rolls 28 are journaled in suitable bearings (not shown) in the pot and guides 29 and 30 between the several sets of rolls tend to confine the strip to a predetermined path through the pot. These rolls are driven by suitable mechanism to feed the strip progressively through the pot. The de-scaled strip traversing the pot 24 is coated uniformly on both sides with a thin layer of zinc, in the known manner.

The strip emerging from the pot 24 passes upwardly therefrom throughout a considerable distance as indicated at 31, free from contact with any support. Eventually, the strip passes over a guide roll 32 so positioned relative to the pot 24 as to provide a cooling zone therebetween of such length that by the time the strip reaches the roll 32, the coating has been cooled and solidified with the accompaniment of the formation of the usual spangles. This prevents the coating from being marked by contact with the roll

32. The roll 32 may be idle or driven, but is preferably driven to reduce the possibility of slippage of the strip thereon.

From the supporting roll 32, the strip passes downwardly to a pinch-roll unit 33 including driven pinch rolls 34 and a guide roll 35. The pinch rolls 34 maintain the portion of the strip between them and the exit rolls 28 of the galvanizing pot substantially taut and deliver the strip to a recoiler 36 of known construction.

Between the pinch-roll unit 33 and the recoiler 36, a shear 37, also of known construction, is disposed. The shear has supporting rolls 38 on opposite sides thereof and is operated to cut out the joints between successive strip lengths, formed by the device 12. Alternatively, the strip may be sheared to length by continued operation of the shear 37. It will be understood that if the strip is to be recoiled after coating, the shear remains stationary with its blades in open position so that the strip may pass freely therebetween.

While the passage of the strip through the several pieces of processing apparatus will in general be continuous, temporary stoppages thereof are obviously necessary to permit joining of successive lengths by the device 12 and the cutting out of the joints by the shear 37. To permit such stoppages without interfering with continuous progress of the strip through the descaler and galvanizing pot, loops of surplus material 39 and 40 may be gathered between the device 12 and the descaling apparatus 16 and between the pinch-roll unit 33 and the shear 37.

Referring now to Figs. 2 and 3 showing a modified apparatus, an uncoiler 40 is adapted to support a coil 41 as it is being unwound. The strip is unwound from the coil by pinch rolls 42 and is passed through a roller leveler 43. After passing through the leveler, the strip enters a bending and brushing unit 44. Pinch rolls 45 feed the strip between guides 46 and around bending rolls 47 and 48. These rolls are magnetic and we provide means for magnetizing them successively in order to feed the leading end of the coiled strip therebetween.

When the leading end of the coil approaches the roll 47, it is magnetized, thereby attracting the strip end and carrying it around the roll. When the leading end of the strip approaches the median plane between the rolls 47 and 48, the roll 47 is de-magnetized and the roll 48 is magnetized. The leading end of the strip is thus passed from the roll 47 to the roll 48.

Guides 49 lead the strip from the roll 48 between exit pinch rolls 50, the roll 48 being demagnetized when the leading end of the strip approaches the guides 49.

Rotary wire brushes 51 adjacent the rolls 47 and 48 perform the same function on the strip as the rolls 22 of Fig. 1, i. e., subject it to a vigorous brushing while it is convexly bent, thereby removing the scale from both surfaces of the strip.

The strip enters a roller leveler 52 after leaving the bending and brushing unit 44. The leveler 52 includes pinch rolls 53 and leveling rolls 54.

The strip issuing from the leveler 52 enters a flying shear 55 of known construction and is there cut to suitable sheet lengths which are successively carried away by a belt conveyor 56.

The conveyor 56 delivers the sheets to a galvanizing pot 57. The pot is supported in a setting 58. Pinch rolls 59 deliver sheets from the conveyor 56 through guides 60 to entry rolls 61 of the galvanizing pot. Bottom rolls 62 and exit rolls 63 convey the sheets through the spelter bath in the pot 57, the path of the sheets being determined by guides 64 and 65.

Sheets discharged from the exit rolls 63 of the galvanizing pot are diverted on to a spangle-forming conveyor 66 by a deflector guide 67. The coated sheets are cooled as they travel along the conveyor 67 and the customary spangles have fully formed by the time they reach the discharge

15 end thereof. The partly cooled and coated sheets are then passed through a roller leveler 68 and delivered immediately on to a roll table 69 from which they are picked up successively by a cooling rack or wheel 70. This device is of well-known construction and comprises lateral arms 71 arranged in rows on a rotating shaft 72 at one side of the roll table 69. The cooling wheel travels at a relatively low speed and the sheets are cooled by contact with the air as the wheel turns. The sheets are finally removed from the wheel by hand.

It will be apparent from the foregoing description that the invention is characterized by numerous advantages over the apparatus used heretofore in coating sheet metal. In the first place, the cost of the descaling operation carried out according to our invention is much less than that of the ordinary acid pickling. The apparatus is much less costly and more compact and 30 may be operated at higher strip speeds (i. e., 300 feet per minute) than have been obtainable in the conventional pickling lines. A further advantage of great importance is that the coating produced by our apparatus exhibits greater adherence to the base metal than the coating applied to material subjected to the conventional acid pickling. Because of its small size, the descaling apparatus may be fully enclosed as indicated in the drawings so that working conditions 40 in the neighborhood are not objectionable. The operating personnel required by the apparatus is much smaller than that required by the usual pickling line.

Although we have illustrated and described 50 but a preferred embodiment and practice of the invention, it will be understood that changes in the construction and operation of the various pieces of apparatus may be made without departing from the spirit of the invention or the scope of the appended claim. In the claim, the term "strip" is intended to include wire as well as thin, sheet metal.

We claim:

60 Apparatus for coating metal strip comprising spaced rolls and means for bending the strip progressively around said rolls in opposite directions, said rolls being small enough to cause fragmentation and at least partial detachment of the scale adhering to the strip, rotary wire brushes engaging the strip at points where it is convexly bent around said rolls and a coating bath adapted to be traversed progressively by the strip.
